DESCRIPTION

U.S. PATENT DOCUMENTS

D22,003 S * 11/1892 Rodiger D19/83
D60,498 S * 2/1922 Mitz D19/83

FIG. 1 is a perspective view of a surface pattern for a storage container for a personal care product; and,
FIG. 2 is a perspective view of a second embodiment thereof.

Features shown in dash lines depict the environment and do not form part of the claimed design.
